CLAIM

The ornamental design for a stator for a vehicle rotary electric machine, as shown.

DESCRIPTION

This application is also related to U.S. Design Patent Application No. now U.S. Pat. No. 29,325,970 filed simultaneously on Dec. 30, 2009 with the present application and entitled “Stator for a Vehicle Rotary Electric Machine”. This application is also related to U.S. Design patent application Ser. No. 29/309,962 filed on Nov. 20, 2008 and entitled Stator for a Vehicle Rotary Electric Machine.

FIG. 1 is a front perspective view of a stator for a vehicle rotary electric machine showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;
